SCRAP BUNCH FEED

Hjalmar Erik Carlson, Brooklyn, N. Y., assignor to International Cigar Machinery Company, a corporation of New Jersey

Application June 18, 1932. Serial No. 618,070

23 Claims. (Cl. 131—42)

This invention relates to an improved filler feed for cigar bunch making machines, particularly for feeding scrap tobacco, its main object being to keep each measured bunch charge under complete control from the time it is received by the density measuring chamber of the bunch forming machine until it is delivered to the loop or bight of the chianti belt in which it is rolled in a "binder" to form a bunch. With this and other objects not specifically mentioned in view, the invention consists in certain constructions hereinafter fully described and then specifically set forth in the claims hereunto appended.

In former scrap bunch feeds, the charge, after it is measured, is taken from the density measuring chamber to the chianti belt by a separate transfer which, on turning into the vertical position, throws the charge into the loop of the chianti belt, thereby disturbing its orderly arrangement and resulting in loose particles between the filler and the binder when the charge is rolled. To overcome this disadvantage, the present filler feed is designed to keep the measured charge confined while being transferred and until after it has been inserted into the loop of the chianti belt, this object in the present invention being achieved by adapting the density measuring chamber itself to act as a transfer for the charge.

The improved density measuring chamber may be provided with a movable gate and is mounted on horizontal shafts carried by a reciprocating frame and equipped with guides in such a manner that on the downward movement of the said shafts the measuring chamber turns from the horizontal tobacco-receiving position to the vertical charge-delivering position, the said gate being so controlled by the charge-cutting knife and by suitable holding means that it closes the measuring chamber immediately upon the knife severing the measured charge and keeps it closed until it has entered the loop of the chianti belt and has nearly reached its lowermost position in the same, ready to leave the charge in the loop as it ascends, the charge being fed into the chamber against a weight-controlled resilient measuring wall which, on the opening of the gate, is pushed outward by suitably arranged springs to deliver the charge in the loop.

In the accompanying drawings,

Fig. 1 is a sectional side elevation of the improved scrap bunch feed equipped with the improved density measuring chamber;

Fig. 2 is an end elevation of the improved measuring chamber showing the means employed

for effecting its vertical swinging transfer motion;

Fig. 3 is a detail side elevation of the gate-operating means taken on line 3—3 of Fig. 2;

Fig. 4 is a sectional view of the measuring chamber taken on line 4—4 of Fig. 2;

Fig. 5 is a sectional view of the measuring chamber on line 5—5 of Fig. 2;

Figs. 6 to 9 are side elevations of the measuring chamber in different positions of its transfer motion, showing the operation of the chamber-swinging and gate-actuating means;

Fig. 10 is a sectional end view of the feed-drum drive taken on line 10—10 of Fig. 1;

Fig. 11 is a sectional end elevation of the tobacco magazine, showing a modification of the device for feeding the tobacco therefrom;

Fig. 12 is a side elevation of the device shown in Fig. 11;

Fig. 13 is a sectional side elevation of the measuring chamber, showing a modification in its construction and in its operating means, taken on line 13—13 of Fig. 14; and

Fig. 14 is an end elevation of the modified measuring chamber shown in Fig. 13.

In carrying the invention into effect there is provided a density measuring chamber having a resiliently mounted wall, means for continuously feeding filler tobacco into said chamber against said wall, a gate pivoted on said chamber, mechanism for cutting off the filler in said chamber and swinging the gate into position to confine the severed charge in said chamber, and means actuated by said yielding wall for stopping said feeding means when the filler tobacco in said chamber reaches a predetermined density. In the best forms of construction contemplated there is also provided a chianti belt, means for lowering said chamber into engagement with said belt and swinging it into charge ejecting position, and means for swinging said gate out of charge confining position to permit said wall to eject the charge onto said belt. These various means and parts may be widely varied in construction within the scope of the claims, for the particular device selected to illustrate the invention is but one of many possible concrete embodiments of the same. The invention, therefore, is not to be restricted to the specific construction shown and described.

Referring to Fig. 1, the scrap filler tobacco T is placed in a feed hopper 10 which in the case illustrated is cylindrical and has radial agitating rods 11 mounted on a hub 12 on shaft 13 and rotated in the counter-clockwise direction by a

chain 14 from the main shaft 15 of the scrap bunch feed which is driven by a chain 16 from the drive shaft 9 of the bunch machine. Star wheels 17 mounted on a shaft 18 and having 5 guide blades 19 from the front wall of magazine 10 between them, are driven in the clockwise direction by a chain 20 from shaft 21, thereby feeding the tobacco into a feed channel formed between a horizontal endless belt 22 and a number 10 of endless chains 23 by adjustable side walls 24 which regulate the width of the feed channel for the length of the bunch to be made. The feed belt 22 is driven by a feed drum 25 on shaft 15 and is guided by pulleys 26, 27, and 28. The 15 chains 23 run over sprockets 29, 30, and 31 on shafts 21, 32, and 33, respectively, and are tensioned by a roller 34 on arms 35; and are driven by a gear 36 on shaft 32 meshing with a gear 37 on shaft 33 which is driven by a chain 39 from shaft 20 15.

The filler tobacco T, on leaving the feed belt 22, passes over the guide bar 40 surrounding the forward side of roller 27 and forming a ledger plate for the knife 58 hereinafter described, and enters 25 the density measuring chamber 41 in which it moves a measuring wall 42 against the pressure produced by an adjustable weight 43, as herein-after described, the measuring wall 42 having attached to its guide rod 44 a finger 45 engaging 30 with the end of a vertical arm 47 mounted on a shaft 48 which is supported by the frame of the bunch machine and carries a crank arm 49 connected by a rod 50 to an arm 51 on shaft 52 on which is fixed the arm 53 carrying the weight 35 43. When the tobacco T entering the chamber 41 has raised the weight 43 to a given height at which the "charge" in chamber 41 is of a predetermined density suitable for the bunches to be made, a cam 54 on shaft 52 allows a spring 55 40 to release a pawl 56 held by the cam against a ratchet 57, loose on shaft 15 but connected with it through planetary gears, as herein-after described, thereby releasing the said ratchet and stopping the motion of shaft 15. Thereupon the 45 knife 58, which is mounted on the vertically reciprocating knife frame 46 actuated by means herein-after described, descends and cuts off the charge. The cam 59 on shaft 60, driven by chain 50 61 from the drive shaft 9 of the bunch machine, by means of cam roller 62 and cam lever 63 ful-crumed on shaft 64 actuates the vertical sliding frame 65 which carries the measuring chamber 41, causing the latter to swing downwards and form a loop 66 in the chianti belt 67, of a bunch 55 rolling mechanism of the well known chianti belt type, the loop 66 being formed between the end of the rolling-table 68 and the rolling-pin 69 by the descent of the measuring chamber. When 60 the knife descends to cut the charge, it closes the gate 70 of the measuring chamber, by means herein-after described, so that the charge is confined in the chamber from the moment the latter commences its descending movement until it has 65 reached its discharge position 41', in arriving at which the gate is automatically opened, by a device herein-after described, so that the charge T' may be expelled into the loop of the chianti belt by spring 71 bearing against the measuring wall 42.

The pawl 56, which has a number of teeth fitting snugly into those of the ratchet 57 to prevent lost motion of the latter, is attached to a curved arm 107 pivoted on a stud 108 in the frame of the machine, the arm 107 on its free end beyond the pivot carrying a roller 109. A

sprocket 110, Figs. 1 and 10, driven by chain 16 from the main shaft 9, is loose on shaft 15 and carries, loosely mounted on a stud 111 thereon, the planetary gears 112 and 113 meshing with the sun gears 114 and 115 respectively on shaft 15, the former gear fast on shaft 15 and the latter integral with ratchet 57. When the pawl 56 is lifted off the ratchet 57 by the spring 55, as the filler tobacco attains the predetermined density in the chamber 41, the motion of the sprocket 110 is transmitted to the gear 115 on ratchet 51 instead of to the gear 114 fast on shaft 15, and the shaft 15 ceases to revolve, thus stopping feed drum 25. On stud 111 extending from sprocket 110 is supported a roller 116 which at the proper moment, once in each cycle when arriving in position 116', Fig. 1, engages with the roller 109, then in its tripped position 109', thereby resetting the pawl 56, and thus, by the action of the planetary gears, to restart the turning of the tobacco-feed shaft 15. The weight 43 having reset the cam 52 the crank arm 49, and the measuring arm 47 after the disengagement of the latter from finger 45, upon the downward movement of the measuring chamber 41, the feed is in position for the next charge as soon as the measuring chamber has returned to starting position which occurs shortly before the engagement of roller 116 with roller 109, the motion of shaft 60, which 105 is also driven from shaft 9, being properly synchronized with the motion of shaft 15.

The measuring chamber, Figs. 2 to 5, consists of a spacing block 72 to which a bottom plate 41 and a top plate 73 are attached by bolts 74. 110 Between the plates 41 and 73 is slidable the measuring wall 42 which is guided by the rod 44 attached to it, and against which the plungers 75 are pressed by compression springs 71 passing through holes provided for this purpose in block 72 and resting against brackets 76 clamped into grooves in plate 41 by the bolts 74. To the end of rod 44 protruding from block 72 is fastened the finger 45 which engages with the arm 47 and thereby connects the measuring chamber 120 with the density-controlling weight 43.

With each end of the block 72 is integral a bracket 77 by which brackets the measuring chamber is pivoted on two coaxial horizontal shafts 78 journaled in the vertical rails 65 which, 125 with their connecting yoke 79, constitute the sliding frame for the measuring chamber. The rails 65 slide in guides 80 attached to the frame 81 of the machine, their up-and-down motion being controlled by cam 59 on shaft 60 through cam 130 roller 62, bell-crank lever 63 on shaft 64, swivel pin 82, adjustable connecting bolt 83, and stud 84.

To the brackets 77 are attached angle bars 85 fitting between the plates 41 and 73 of the measuring chamber and forming the end walls of the 135 same, one of the said angle bars being made interchangeable to suit different widths of tobacco charges and for different widths of tobacco charges for different lengths of bunches, the measuring wall 42, which fits into the space between the angle bars 85, being also made interchangeable by providing a number of extra holes 86 in block 72 for the passage of one of the springs 71 with its plunger 75.

At their outer ends each of the pivot shafts 78 145 carries a cam piece 87 and a guide block 88, the former adapted to engage with stationary pins 89 and the latter with stationary guides 90 carried by frame 81. The cam pieces 87 are designed to turn the measuring chamber from the 150

horizontal to the vertical position as the sliding frame 65 starts on its downward movement, and the guide blocks 88 serve to hold the chamber in the vertical position the remainder of the way.

5 The inner ends of the shafts 78, adjacent to the measuring chamber, carry loosely mounted brackets 91 to which the gate 70 of the measuring chamber is attached and each of which carries a horizontally projecting pin 92. The hub 10 of each of the brackets 91 has two axial V-grooves 93, 93' adapted to engage with a ball 94 bearing against the circumference of the hub by means of a coil spring 95 imbedded in a socket of brackets 77, one of the said grooves registering with 10 the said ball when the gate is open and the other when the gate is closed. Instead of the grooves 93, flat surfaces may be provided on the circumferences of the hubs, the flats of each hub engaging with a leaf spring mounted on brackets 77, 15 to hold the brackets 91 in either the open or closed position of the gate.

The sliding frame 46 of knife 58, which is actuated by a cam lever 96 on shaft 64 having a cam roller 97 engaging with a track in cam 59 on shaft 60, Fig. 1, on each side has two noses 98 and 99 adapted to engage with the pins 92 in brackets 91, the upper noses 98 closing the gate 70 on the descent of the knife and the lower noses 99 opening the gate on its ascent. To the sides 30 of the rolling table 68 are stationarily attached cam pieces 100 adapted to engage the pins 92 and thereby to open the gate 70 when the chamber 41 arrives at its lowermost position in the loop 66 of the rolling apron.

35 The charge expelled by the measuring chamber is of a rectangular cross-section, the long side of which, for a given diameter of cigar bunch, is the greater, the smaller the height of the measuring chamber. In order to compress 40 this rectangular cross-section into a more or less square form approaching the final circular shape of the bunch into which it is to be rolled by the chianti belt, a movable vertical wall 101 extending across the entire width of the chianti belt 67 is supported near the loop 66 by vertical arms 102 pivoted on shaft 103. The arms 102 are held against the rear of rolling pin 69 by springs 104, so that on the forward motion of pin 69 the wall 101 bears against loop 67 and compresses 45 the charge T', which then, by the shortening of the loop, has been raised and turned into a position in which the long side of the rectangular cross-section, is substantially horizontal, into a more or less square cross-section before the pin 50 69 closes the loop, a stop 105 being provided to arrest the forward motion of wall 101 when its compressing action has sufficiently accomplished 55 its purpose.

60 When the measuring chamber 41 is in the horizontal tobacco-receiving position, Fig. 6, the cam pieces 87 are in engagement with pins 89 so that, upon the descent of the sliding frame 65, after the automatic stopping of the feed and the cutting 65 of the charge, the measuring chamber, besides descending, immediately begins to turn, its gate 70 having been closed upon the descent of the knife 58 by the engagement of the upper noses 98 of the knife frame 46 with the pins 92 of the gate brackets 91, as shown in dotted lines 70 in Fig. 7. As the gate 70 closes, the balls 94 on the hubs of brackets 91, which are lifted out of the first grooves 93 by the turning of the brackets, drop into the second grooves 93', Fig. 7, thereby holding the gate closed after the measuring chamber leaves the horizontal position, the lower

noses 99, which have the function to open the gate 70 upon the ascent of the knife prior to the re-starting of the feed, being shaped so as to clear the pins 92 upon the turning of the measuring chamber.

The closed measuring chamber now completes its downward turn by means of the engagement of cam pieces 87 with pins 89 and when arrived in the vertical position, Fig. 8, the cams 87 leave pins 89 and the guide blocks 88 engage with the guides 90, thereby holding the chamber in vertical position during the remainder of its downward travel during which it depresses the rolling-apron 67, forming therein the loop 66. Shortly before the measuring chamber reaches its lowermost position, Fig. 9, the pins 92 engage with cam-brackets 100, attached to the sides of rolling table 68, thereby opening the gate 70 while the chamber advances to the end of its stroke. The charge in chamber 41 is then expelled, on the ensuing upward motion of the chamber, by the action of the springs 71 which hold the measuring wall 42 against the charge in loop 66 until the chamber has risen above the charge, whereupon the chamber returns to its charge-receiving position, the cam pieces 87 reengaging pins 89 on its upward move and thereby turning the chamber into its horizontal position. On arriving in the latter position, the pins 92 engage with the noses 98 of the knife frame 46 which has remained in its down position during the entire travel of the measuring chamber, thus closing the gate 70, as shown in dotted lines in Fig. 9. Upon the then ensuing ascent of the knife 58, the lower noses 99 engage the pins 92 and restore the gate into its open position, Fig. 6, ready for the next cycle of operations.

After the measuring chamber on its ascent has cleared the rolling-table 68, the rolling-pin 69 moves over the latter thereby doubling the apron 67 which then is supported on the rod 106, over the charge in loop 66 and rolling the charge in the loop over the flat portion of the rolling-apron upon which a binder leaf has previously been deposited, thus producing a bunch which is discharged into a cradle, not shown, at the end of the table 68 by the movement of the rolling-pin.

The knife 58, by means of cam 59 and cam lever 96 is timed to operate at a given point of the cycle 125 just prior to the descending movement of the measuring chamber 41 effected by cam lever 63 actuated by the same cam 59, the said operating point being so chosen as to allow ample time for the chamber to fill under even the worst possible conditions. Under normal conditions, therefore, the filled chamber will cause the arm 49 to release the pawl 56 and thereby stop the tobacco feed some time before the knife is operated and before the chamber then commences its descent, this intervening time interval being the greater than any possible variation in time required to fill the chamber.

The tobacco charge, being confined in the measuring chamber from the time it is cut off from the feed layer to the time it is orderly deposited into the rolling-apron loop, thus is kept perfectly intact and all disarrangement of the charge with its resulting disadvantages is eliminated by the improved arrangement of the measuring chamber.

In Figs. 11 and 12, a modification of the tobacco magazine is shown, the discharge star wheels 17 of Fig. 1 being replaced by an axially reciprocating agitator 117 which may be made circumferentially stationary as shown, or provided with a ro-

ary motion as well by retaining the chain 20 of Fig. 1, a driven sprocket, not shown, then being splined to shaft 18 and held against one of the pedestals 118 by a suitable stationary member. The agitator 117 consists of a cylinder of suitable length having a serrated, grooved or otherwise roughened surface, its shaft ends 18 being slidably supported in bearings provided in the pedestals 118 of the magazine shaft 13. One of the ends of the shaft 18 carries a collared shift sleeve 119 with which engages the rounded end 120 of a cam lever 12, the other end of which has a roller 122 in engagement with the wave-shaped track of a cam 123, the said lever 121 being fulcrumed on a bracket 124 attached to pedestal 118. The shaft 125 of cam 123 is supported by a bracket of pedestal 118 and is driven by a chain 126 connecting a sprocket 127 on the cam shaft 125 with a sprocket 128 on shaft 13 and chain 14 drives shaft 13 to rotate the radial agitators 11 on hub 12. To prevent tobacco from being spilled sideways beyond the edges of feed belt 22 by the agitator 117, side guides 129 are provided which strip the agitator as it passes through them.

The gate 70 of the measuring chamber shown in Figs. 2 to 5 may ordinarily be omitted, since under the usual conditions the tobacco in the measuring chamber is packed sufficiently tight to remain undisturbed during the turning of the chamber, while in the vertical position of the chamber the rolling apron 67 forms an efficient closure of the same. The omission of the gate, of course, makes unnecessary the gate opening and closing devices above-described, and the simple measuring chamber shown in Figs. 13 and 14 is obtained, consisting merely of the spacing block 72 with the brackets 77, of the side plates 41 and 73, of the adjustable end bars 85 and of the measuring wall 42 with its guide rod 44 and control finger 45. For expelling the charge, the measuring wall 42 is moved downward by a trip-lever 130 pivoted on a bracket 131 attached to slide frame 65 and bearing on the end of guide rod 44. The lever 130 has a cam extension 132 which at the proper moment engages with a cam piece 133 fastened to the frame 81 of the machine, thereby depressing lever 130 which is held in engaging position with the cam piece 133 by a spring 134 attached to frame 65. A short coil spring 135 placed on guide rod 44 prevents the wall 42 from sticking when at the end of the measuring chamber and returns the wall to the inner end of the measuring chamber upon the ascent of the latter. However, when the measuring chamber arrives in filler receiving position the guide rod is pressed inwardly by the arm 47 to bring the wall 42 to the front end of the measuring chamber. As the filler is fed into the measuring chamber it pushes the wall 42 and arm 47 back against the resistance of the weight 43 until the filler reaches the desired density in the chamber, when the lever 53 carrying weight 43 has been swung sufficiently to permit the cam 54 to release the pawl 56 and stop the filler feed. Thereupon the filler is severed and deposited in the rolling apron by the measuring chamber.

What is claimed is:

1. The combination with a density-measuring chamber having a resiliently mounted yielding wall, of means for continuously feeding filler tobacco into said chamber against said wall, a gate pivoted on said chamber, mechanism for cutting off the filler in said chamber and swinging said

gate into position to confine the severed charge in said chamber, and means actuated by said yielding wall for stopping said feeding means when the filler in said chamber reaches a predetermined density. 80

2. The combination with a density-measuring chamber having a resiliently mounted yielding wall, of means for continuously feeding filler tobacco into said chamber against said wall, a gate pivoted on said chamber, mechanism for cutting off the filler in said chamber and swinging said gate into position to confine the severed charge in said chamber, and means actuated by said yielding wall for stopping said feeding means when the filler in said chamber reaches a predetermined density, said mechanism including a knife frame having a knife adapted to cut off the filler in said chamber, and means for reciprocating said knife frame to sever the filler tobacco. 85

3. The combination with a density-measuring chamber having a resiliently mounted wall, of means for feeding filler tobacco into said chamber against said wall, and mechanism for stopping said means when the filler in said chamber reaches a predetermined density, said chamber having a spring-pressed guide rod passing therethrough and fixed to said wall, said rod being provided with an outwardly extending finger, and said filler feeding means including a filler feeding belt, and said mechanism including a planetary gear drive for said belt, and means engaged by said finger for stopping said planetary gear drive when the filler in said chamber reaches a predetermined density. 90

4. The combination with a density-measuring chamber adapted to receive a charge of filler tobacco and having a wall resiliently mounted therein, of a gate pivoted on said chamber, means for swinging said gate about its pivot into position to confine the charge in said chamber, means for simultaneously lowering and turning said chamber to bring it into charge ejecting position, and a device for swinging said gate out of charge confining position to permit the charge to be ejected from said chamber by said wall. 105

5. The combination with a density-measuring chamber adapted to receive a charge of filler tobacco and having a wall resiliently mounted therein, of a gate pivoted on said chamber, means for swinging said gate about its pivot into position to confine the charge in said chamber, means for simultaneously lowering and turning said chamber to bring it into charge ejecting position, and a device for swinging said gate out of charge confining position to permit the charge to be ejected from said chamber by said wall, said chamber lowering and turning means including a reciprocating frame in which said chamber is pivoted, cam pieces on said chamber, and stationary pins adapted to engage said cam pieces to turn said chamber while it is being lowered. 115

6. The combination with a density-measuring chamber adapted to receive a charge of filler tobacco and having a wall resiliently mounted therein, of a gate pivoted on said chamber, means for swinging said gate about its pivot into position to confine the charge in said chamber, means for simultaneously lowering and turning said chamber to bring it into charge ejecting position, and a device for swinging said gate out of charge confining position to permit the charge to be ejected from said chamber by said wall, said device including a stationary cam bracket 120

adapted to engage said gate to swing it out of charge confining position.

7. The combination with a chianti belt, of a
rolling table, a density-measuring chamber hav-
ing a resiliently mounted wall, means for continu-
ously feeding filler tobacco into said chamber
against said wall, a gate pivoted on said cham-
ber, mechanism for cutting off the filler in said
chamber and swinging said gate into position to
10 confine the severed charge in said chamber,
means actuated by said wall for stopping said
filler feeding means when the filler in said cham-
ber reaches a predetermined density, means for
lowering said chamber into engagement with said
15 belt, means for turning said chamber into charge
ejecting position while it is being lowered, and
a device on said table for swinging said gate out
of charge confining position to permit said wall
to eject the charge.

20 to eject the charge.

25 8. The combination with a chianti belt, of a
rolling table, a density-measuring chamber hav-
ing a resiliently mounted wall, means for con-
tinuously feeding filler tobacco into said cham-
ber against said wall, a gate pivoted on said
chamber, mechanism for cutting off the filler in
said chamber and swinging said gate into posi-
tion to confine the severed charge in said cham-
ber, means actuated by said wall for stopping
said filler feeding means when the filler in said
30 chamber reaches a predetermined density, means
for lowering said chamber into engagement with
said belt, means for turning said chamber into
charge ejecting position while it is being low-
ered, and a device on said table for swinging said
35 gate out of charge confining position to permit
said wall to eject the charge, said mechanism in-
cluding a knife frame having a knife adapted to
sever filler in said chamber, means for recip-
rocating said frame to cut off the filler in said
40 chamber, and means on said knife frame for
swinging said gate about its pivot into position
to confine the severed charge in said chamber.

43 9. The combination with a chianti belt, of a
rolling table, a density-measuring chamber hav-
ing a resiliently mounted wall, means for con-
tinuously feeding filler tobacco into said cham-
ber against said wall, a gate pivoted on said cham-
ber, mechanism for cutting off the filler in said
chamber and swinging said gate into position
50 to confine the severed charge in said chamber,
means actuated by said wall for stopping said
filler feeding means when the filler in said cham-
ber reaches a predetermined density, means for
lowering said chamber into engagement with said
55 belt, means for turning said chamber into charge
ejecting position while it is being lowered, and
a device on said table for swinging said gate out
of charge confining position to permit said wall
to eject the charge, said lowering means includ-
60 ing a sliding frame on which said chamber is
pivoted, and cam means for reciprocating said
frame, and said turning means including cam
pieces on said chamber and stationary pins en-
gaging said cam pieces.

gaging said can pieces.

65 10. The combination with a chianti belt, of a
rolling table, a density-measuring chamber hav-
ing a resiliently mounted wall, means for con-
tinuously feeding filler tobacco into said cham-
ber against said wall, a gate pivoted on said cham-
ber, mechanism for cutting off the filler in said
70 chamber and swinging said gate into position
to confine the severed charge in said chamber,
means actuated by said wall for stopping said
filler feeding means when the filler in said cham-
75 ber reached a predetermined density, means for

lowering said chamber into engagement with said belt, means for turning said chamber into charge ejecting position while it is being lowered, and a device on said table for swinging said gate out of charge confining position to permit said wall to eject the charge, said device including stationary cam brackets arranged on said table to engage said gate and swing it out of charge confining position.

11. The combination with a rolling table of a chianti belt overhanging one end of said table, means for depressing the portion of said belt overhanging said table to form a loop therein and delivering a charge of tobacco into said loop, and means for compressing the charge in said loop against the end of said table. 85 90

12. The combination with a density-measuring chamber having a yielding wall, of means for feeding filler tobacco into said chamber against said wall, said wall having an outwardly extending finger connected thereto, and said means including a shaft, a feed drum on said shaft, a filler feeding belt running over said drum and adapted to feed filler tobacco into said chamber, a driven sprocket loosely mounted on said shaft, a ratchet 100 loosely mounted on said shaft and having a gear integral therewith, a sun gear fixed on said shaft, a stud on said sprocket carrying planetary gears engaging with said sun gear and the gear integral with said ratchet, a pivoted arm carrying 105 a pawl at one end and a roller at its other end, a cam adapted to engage said pawl, a weighted lever connected to said cam to move it out of engagement with said pawl, a measuring arm engaging said finger, and linkage connecting said 110 measuring arm and cam, whereby said cam will be moved into position to press said pawl against said ratchet when the filler tobacco attains the predetermined density in said chamber, a spring connected to said arm adjacent said pawl to withdraw it from said ratchet, and a roller on said 115 stud arranged to engage the roller on said arm to press the pawl against said ratchet against the tension of said spring.

13. The combination with a density measuring chamber having a wall mounted to yield under pressure, of means for continuously feeding tobacco into said chamber against said wall, mechanism for cutting off the filler in said chamber, means actuated by said yielding wall for stopping said feeding means when the filler in said chamber reaches a predetermined density, a chianti belt arranged to receive the filler and means for moving said chamber into engagement with said belt to depress it to form a loop therein and then withdraw said chamber to permit said wall to eject the filler into said loop. 120 125 130

14. The combination with a density measuring chamber having a wall yieldingly mounted therein, of means for continuously feeding tobacco into said chamber against said wall, mechanism for cutting off the filler in said chamber, means actuated by said wall for stopping said feeding means when the filler in said chamber reaches a predetermined density, a chianti belt arranged to receive the filler, means for moving said chamber into engagement with said belt to depress it to form a loop therein, and a device for giving said wall a movement to eject the filler into said loop. 135 140

15. The combination with a density measuring chamber having a wall yieldingly mounted therein, of means for continuously feeding tobacco into said chamber against said wall, mechanism for cutting off the filler in said chamber, means actuated by said wall for stopping said feeding 145

means when the filler in said chamber reaches a predetermined density, a chianti belt arranged to receive the filler, means for moving said chamber into engagement with said belt to depress it to form a loop therein, and a device for giving said wall a movement to eject the filler into said loop, said device including spring-pressed plungers bearing against said wall.

16. The combination with a density measuring chamber having a wall mounted therein, of means for continuously feeding tobacco into said chamber against said wall, mechanism for cutting off the filler in said chamber, means actuated by said wall for stopping said feeding means when the filler in said chamber reaches a predetermined density, a chianti belt arranged to receive the filler, means for moving said chamber into engagement with said belt to depress it to form a loop therein, and a device for giving said wall a movement to eject the filler into said loop, said device including a reciprocating frame in which said chamber is mounted, a guide rod slidably mounted in said chamber and secured to said wall, a stationary cam piece, a trip-lever pivoted on said frame and adapted to engage said cam piece during the movement of said frame, and a spring yieldingly urging said trip-lever into engagement with said cam piece, whereby engagement of the trip-lever with the cam piece during the downward movement of the frame will press the lever against the guide rod and move the wall outwardly to eject the charge into the loop.

17. The combination with a rolling table, of a chianti belt, a rolling pin coating with said belt to roll a bunch in a loop of the belt, and a movable spring-pressed element arranged to engage and exert pressure on the loop to distribute and round the material of the bunch.

18. The combination with a density-measuring chamber having an end wall resiliently mounted therein and adapted to receive a charge of filler tobacco, of a chianti belt, and means for lowering said chamber into engagement with said belt to depress it to form a loop therein and then withdraw said chamber to permit said wall to eject the charge into said loop.

19. The combination with a density-measuring chamber adapted to receive a charge of filler tobacco while it is in a horizontal position and having a wall resiliently mounted therein, of means for simultaneously lowering and turning said

chamber to bring it into vertical charge ejecting position, said means including a reciprocating frame in which said chamber is pivoted, cam pieces on said chamber, stationary pins adapted to engage said cam pieces to turn said chamber while it is being lowered, vertical stationary guides, and guide blocks on said chamber adapted to engage said guides to hold the chamber in vertical position after said cam pieces disengage said pins on the continued downward movement of said frame.

20. The combination with a density-measuring chamber having a wall movably mounted therein, of means for continuously feeding filler tobacco into said chamber against said wall, mechanism for cutting off the filler in said chamber, and means actuated by said wall for stopping said filler feeding means, said feeding means including a filler feeding belt, a magazine arranged to deliver filler tobacco to said belt, a driven shaft in said magazine, radial rods on said shaft adapted to agitate the tobacco in the magazine, a plurality of driven chains cooperating with said belt to feed the filler tobacco to said chamber, and an axially reciprocating grooved roller for agitating the tobacco on said belt before it reaches said chains.

21. Means for feeding filler tobacco comprising a filler tobacco feeding belt, a magazine arranged to deliver filler tobacco to said belt, a driven shaft in said magazine, radial rods on said shaft adapted to agitate the tobacco in said magazine, a plurality of driven chains cooperating with said belt to feed the tobacco, a grooved roller axially reciprocating transversely of said belt for agitating the tobacco on said belt before it reaches said chains, and means for reciprocating said roller axially.

22. Means for feeding filler tobacco, comprising a filler tobacco feeding belt, a magazine having an outlet arranged to deliver filler tobacco to said belt, a grooved roller extending transversely above said belt beyond said outlet, and means for reciprocating said roller axially to level off the tobacco on said belt.

23. Means for feeding filler tobacco, comprising a filler tobacco feeding belt, a grooved roller extending transversely above said belt, and means for reciprocating said roller axially to level off the tobacco on said belt.

HJALMAR E. CARLSON.
